CLAIM

I claim the ornamental design for a roll-up door with corrugated drum, as shown and described.

DESCRIPTION

FIG. 1 is an inside perspective view of a roll-up door with corrugated drum showing the claimed design.

FIG. 2 is an inside elevational view of the claimed design.

FIG. 3 is a left-side profile view of the claimed design, the right side being a minor image.

FIG. 4 is an outside elevational view of the claimed design.

FIG. 5 is a top plan view of the claimed design.

FIG. 6 is a bottom plan view of the claimed design; and, FIG. 7 is a close-up view of a portion of the claimed design illustrated in FIG. 3.

In the drawings, the broken lines are for the purpose of showing environmental structure and form no part of the claimed design.

The dash-dot-dash broken lines in FIGS. 2 & 4 depict portions of the roll-up door with corrugated drum that form no part of the claimed design. The dash-dot-dash broken lines in FIGS. 3 & 7 depict the limits of the enlarged view and form no part of the claimed design.
